UNITED STATES PATENT OFFICE.

ARTHUR SCHIEBEL, OF ASTORIA, NEW YORK.

COMBINATION-BRUSH.

1,012,281.

Specification of Letters Patent. Patented Dec. 19, 1911.

Application filed October 19, 1911. Serial No. 655,473.

To all whom it may concern:

Be it known that I, ARTHUR SCHIEBEL, a subject of the German Emperor, residing at Astoria, Long Island, in the county of 5 Queens and State of New York, have invented certain new and useful Improvements in Combination-Brushes, of which the following is a specification.

The present invention relates to a brush 10 for cooking or baking utensils and has for its object to combine the same with a scraper and sweeper, so that the brushing, scraping and sweeping may be accomplished simultaneously.

15 To make my invention more clear, the same is illustrated in the accompanying drawing, in which similar reference letters denote corresponding parts and in which—

Figure 1 is a side elevation; Fig. 2 is an 20 end view; Fig. 3 is an elevation of the device seen from the side opposite to that of Fig. 1 and Fig. 4 is a bottom plan view.

In my new brush, the brush proper may be of ordinary construction and consist of 25 split cane *a* or the like fixed to a wooden stock *b*. At one side, a metal blade *c* provided with vertical slots *c'* is secured by set screws *d* to the stock *b* and serves as a

scraper. Owing to the slots *c'* and set screws *d*, the blade is capable of adjustment in vertical direction. At the opposite side of the stock, the sweeper is provided, which consists of two or more pieces *d'* of felt or other material, which are removably clamped between the brush and an adjustable metal plate *e* by means of screws *f*. The felt pieces project somewhat below the flexible ends of the brush.

What I claim and desire to secure by Letters Patent is:

A brush for cooking or bakery utensils, comprising a block, brush bristles secured in said block, a scraper plate adjustably secured to one side of the said block, strips of soft material at the opposite side of the 45 said block adapted to project somewhat below the brush bristles and serving as a sweeper and a metal plate secured to said block and adapted to clamp the said soft material between itself and the said block. 50

In testimony whereof I affix my signature in presence of two witnesses.

ARTHUR SCHIEBEL.
